DESIGN FOR A SHOELACE TASSEL

Clifford G. King, Warren, R. I.

Application February 23, 1937, Serial No. 67,788

Term of patent 7 years

To all whom it may concern:

Be it known that I, Clifford G. King, a citizen of the United States and resident of Warren, in the county of Bristol and State of Rhode Island, have invented a new, original, and ornamental Design for a Shoe Lace Tassel, of which the following is a specification, reference being had to the accompanying drawing, forming part thereof.

In said drawing, the figure is a perspective view, in elevation of a shoe lace tassel showing my new design; the tassel presents substantially the same appearance in elevation on all sides.

I claim:

The ornamental design for a shoe lace tassel as shown and described.

CLIFFORD G. KING.
